UNITED STATES PATENT OFFICE.

KARL ZIMMERMANN, OF ST. GREGOR, SASKATCHEWAN, CANADA.

LEATHER-SPLITTING MACHINE.

1,326,317.

Specification of Letters Patent. Patented Dec. 30, 1919.

Application filed January 17, 1919. Serial No. 271,646.

To all whom it may concern:

Be it known that I, KARL ZIMMERMANN, a citizen of Germany, residing at St. Gregor, in the Province of Saskatchewan, in the Dominion of Canada, have invented certain new and useful Improvements in Leather-Splitting Machines, of which the following is a specification.

This invention relates to improvements in leather splitting or skiving machines and its chief object is to provide a machine of this type that can be adjusted to cut longitudinally or split welts, strips of leather stock or large pieces of leather stock. Means are provided for so adjusting the cutting mechanism that the work may be split into two layers of equal thickness, or that layers of unequal thickness may be cut as desired. With the foregoing and other objects in view the invention consists in the combination and arrangement of parts to be hereinafter fully described, pointed out in the appended claims and illustrated in the accompanying drawings which form a part of this specification and in which—

Figure 1 is a view of my improved machine in side elevation.

Fig. 2 is an end view of the machine with a portion of the rolls broken away to show the knife blade.

Fig. 3 is an enlarged fragmentary view of a type of bearing employed.

Fig. 4 is a vertical sectional view through Fig. 1.

Like reference characters denote corresponding parts throughout the several views.

My machine comprises the frame 1 provided with the apertured feed table 2 having the support 3. The table projects beyond the front end of the frame and is adapted to receive the leather 4 to be cut. The top of the frame is formed with perforations to receive the rolls employed and the sides of the frame are formed with perforations 5, 6 and in the perforations 5, disposed below the table 2, are the two-piece bearings 7, the component parts of said bearings being connected by the bolts 8 which extend through said bearings and into the frame and which are provided with the nuts 9. In each of said bearings one end of one of the shafts 10, 11 is journaled, said shafts extending transversely of the frame 1 and being provided, respectively, with the feed rollers 12, 13, said rollers being fast upon said shafts. Directly above the shafts 10, 11 shafts 14,

15 are arranged in bearings 7^a disposed in perforations 6 of the frame, said bearings 7^a being connected by bolts 7^c and being similar to the bearings 7 except that springs 7^b are arranged upon the bolts 8^a and space the bearings away from the upper end of the perforated portion 6. Upon the shafts 14, 15 gage rollers 16, 17 are made fast. Normally the rollers 16, 17 are kept in frictional engagement with the rollers 12, 13 through gravity and through action of the springs 7^b. The shaft 10 is provided with a pulley 18 adapted to receive power by means of the usual belt running to the engine or motor 70 shaft. The shafts 10, 14 are provided with the large gear wheels 19, 20, the teeth of which are deep set and are constantly in mesh so that the shaft 10 drives the shaft 14. The shafts 10, 11 are provided with 75 small sprocket wheels 21, 22 which are connected by sprocket chain 23^a so that shaft 10 drives the shaft 11. The shafts 14, 15 are each provided with sprocket wheels 23, 24 which are connected by a sprocket chain 25 so that the shaft 14 drives the shaft 15. In the rear end of the frame in perforations 6 two-piece bearings 7^a are arranged upon guide bolts 8^a, springs 7^b serving to yieldingly press said bearings toward the shafts 85 11, 15. Shafts 26, 27 are arranged in the upper and lower portions, respectively, on the rear end of the frame in the bearings 7^a, said shafts carrying the rollers 28, 29 which through the medium of spring 7^b 90 abutting said bearings are yieldingly retained in frictional engagement with the rollers 17, 13. The rollers 28, 29, then, have, as well as their rotary motion, a movement longitudinally of the frame 1.

The said shafts 26, 27 are provided with pulleys 30, 31, the latter being a double pulley, which are connected by belt 32 and the shaft 11 is provided with pulley 34 connected by belt 35 to pulley 31, so that the 100 shafts 26, 27 are driven by the shaft 11. Fast to the shaft 15 is a link 36 which is connected by pivot 37 to a cam gear 38 which is secured by pivot 39 to the frame 1, the teeth of said cam gear being in mesh 105 with the teeth of another cam gear 40 which is arranged upon cam shaft 41 that extends transversely of the frame and is journaled therein, said gear 40 being pivotally connected by screw-bolt 42 to the turnbuckle 43 110 which turnbuckle also receives a screw-bolt 44 which is connected directly to the knife

shaft 45 that is arranged in bearings 46 which are slidingly disposed in perforations 47 formed in the frame 1, springs 49 yieldingly spacing the said sliding bearings away from one end of the perforations 47. The knife 48 extends transversely of the frame 1 and its shaft 45 is supported in the said screw-bolt 44 and in a similar screw-bolt 44^a at the opposite side of the frame with reference to bolt 44, said bolt 44^a engaging a turnbuckle 43^a which is connected also to one end of another screw-bolt 42^a which engages with one end of the cam shaft 41. The knife 48 is provided with the cutting blade 50 which may be inserted into and removed from the knife frame through a perforation 51 formed in the frame 1. The knife blade is disposed normally at the point of contact of the roller 17 with the roller 13. 20 As the leather 4 is moved by hand over the table 2 at the front end of the machine it encounters the rollers 12, 16 between which it is drawn by the movement of said rollers. The rollers are thus spread apart by the work which is fed along the table 2 into engagement with the rollers 13, 17 between which it is forced or drawn, when it is engaged and cut or split by the knife blade 50. The work in passing between the rollers 13, 17 raises the roller 17 slightly together with the shaft 15 which raises the link 36 and partly rotates the cam gear 38 which partially rotates the cam gear 40 and its shaft 41, said cam gear and cam shaft through the medium of the screw-bolts and turnbuckles raising the knife shaft 45 together with the knife and its blade so that the knife blade will be disposed midway, or any other predetermined distance, between the rollers 13, 17 so that it may be properly positioned for operative engagement with the leather. By means of the turnbuckles 43, 43^a and the screw-bolts the knife shaft may be set to follow the upward movement of the roller 17 in a greater or less degree, as desired, so that the leather may be split exactly in half or a relatively thin upper or lower strip may be cut as desired. It is obvious that by means of the turnbuckle the spring 49 may be compressed more or less thus adjusting the knife shaft to follow the movement of the roller 17 at a greater or less distance therefrom. The knife shaft is pivotally supported by the screw-bolts 44, 44^a. The leather passing beyond the knife blade passes over the knife frame, one strip passing between the roller 28 and a work guide 52 to the table 53 and the other strip passing between the roller 29 and a work guide 54 to the said table. The cut leather strips passing beyond the knife frame force the rollers 28, 29 longitudinally of the frame away from the rollers 17, 13.

What is claimed is:—

1. In a leather splitting machine, a frame, a feed table arranged in said frame, a set of feed rollers arranged in said frame below said feed table, a set of gage rollers arranged in said frame above said feed table and adapted for frictional engagement with said feed rollers through openings in said feed table, a pair of guide rollers arranged in the rear end of said frame and yieldingly retained in frictional engagement with said feed and gage rollers, and a knife adjustably supported in said frame, the blade of said knife being positioned adjacent the point of contact of two of said rollers. 65

2. In a leather splitting machine, a frame, a feed table arranged in said frame, a set of feed rollers arranged in said frame below said feed table, a set of gage rollers arranged in said frame above said feed table and adapted for yielding frictional engagement with said feed rollers through openings in said feed table, a knife block, a shaft for said knife block, meshing cam gears pivotally carried by said frame, an adjustable connection between one of said cam gears and said knife shaft, a connection between the other cam gear and the shaft of one of said gage rollers, a pair of guide rollers arranged in the rear end of said frame and yieldingly retained in frictional engagement with said feed and guide rollers, and a blade removably carried by said knife block and disposed adjacent the point of contact of one of said feed rollers with one of said gage rollers. 100

3. In a leather splitting machine, a frame, a feed table arranged in said frame, a set of feed rollers arranged in said frame, a set of gage rollers arranged in said frame for coöperation with said feed rollers, said gage rollers being movable with relation to said feed rollers, a set of guide rollers arranged in said frame for coöperation with said feed and gage rollers, said guide rollers being movable at right angles to the plane of movement of said gage rollers, a knife block arranged in said frame between said gage, feed, and guide rollers, said knife block being adjustably connected to a gage roller to follow the movement of said gage roller at a greater or less distance therefrom, and a blade carried by said knife block, said blade being normally disposed adjacent the point of contact of one of said feed rollers with one gage roller. 105 110 115

4. In a leather splitting machine, a frame, a feed table arranged in said frame, a set of feed rollers arranged in said frame, a set of vertically movable gage rollers arranged in said frame for coöperation with said feed rollers, a set of horizontally movable guide rollers arranged in said frame for coöperation with said feed and gage rollers, 120 125

a knife block carried in said frame connected to a gage roller by connections capable of adjustment to cause it to automatically follow the movement of said gage

5 roller at a greater or less distance therefrom, and a blade carried by said knife block and normally disposed adjacent the point of contact of one of said feed rollers with one gage roller.

In testimony that I claim the foregoing 10 as my own I have hereunto affixed my signature in the presence of two subscribing witnesses.

KARL ZIMMERMANN.
